UNITED STATES PATENT OFFICE.

ALDEN D. KILBORN, OF OAKLAND, CALIFORNIA.

LUBRICATOR.

SPECIFICATION forming part of Letters Patent No. 369,250, dated August 30, 1887.

Application filed June 9, 1887. Serial No. 246,765. (No model.)

To all whom it may concern:

Be it known that I, ALDEN D. KILBORN, of Oakland, in the county of Alameda and State of California, have invented certain new and useful Improvements in Lubricators for Steam-Engines; and I do hereby declare that the following is a full, clear, and exact description of the invention, which will enable others skilled in the art to which it appertains to make and use the same, reference being had to the accompanying drawings, and to the letters of reference marked thereon, which form part of this specification.

This invention relates to certain improvements in oil-cups for automatically feeding lubricating material to machinery of various descriptions; but it is particularly designed for feeding two different classes of lubricant to the guides of locomotives; and it has for its objects to so construct the cup that it cannot be properly charged until the parts are arranged or set for feeding, so as to insure proper work irrespective of any inattention or carelessness on the part of the engineer in charge, as more fully hereinafter described.

The above-mentioned objects are accomplished by the means illustrated in the accompanying drawings, in which—

Figure 1 represents a side elevation of my improved lubricating-cup, with a portion in section, showing a part of the adjusting mechanism. Fig. 2 represents a vertical sectional view of my improved cup, taken on line *x x* of Fig. 1; and Fig. 3, a horizontal cross-section taken on the line *y y* of Fig. 1.

Referring to the drawings, the letter *A* indicates an outer cylindrical cup or other suitably-shaped casing, having a central perforated boss, *a*, at its bottom, which sets in a suitable recess in the machinery to be lubricated. The said outer casing or cup is provided with openings at the sides, as indicated by the letters *b* *c*, for the purpose hereinafter described, and with a screw-cup, *D*, on top, which latter is provided with a central perforated boss, *d*, having an inward extension, *e*, the said extension being provided with a female screw-thread, *g*, into which fits the upper male screw-threaded end of a central tube, *E*, the lower end of which is also externally screw-threaded for the reception of a female

screw-threaded plate, *G*, having a central perforated boss, *h*.

The letter *F* indicates a glass cup, which has a central opening, *i*, at its bottom, through which the tube *E*, before mentioned, passes. The said cup is provided with a flange, *k*, at its bottom edge, between which and the plate *G* is secured a washer, *j*, which may be tightly clamped, so as to prevent any leakage from the glass cup. The tube *E* is provided with openings *m* near its lower end, through which the oil passes from the interior of the glass cup to the valve-opening *n* in the central boss of the plate *G*.

The boss *a* on the lower end of the casing has a central bore, *h'*, the upper end of which is countersunk. A stem, *H*, fits loosely in the bore *h'*, and is prevented from falling out by the pin *h''*, which passes through it, and which engages with the countersunk part of the bore *h'*. The stem *H* extends slightly below the boss *a*, and also extends a short distance into the interior of the cup or casing *A*. The lower part of the stem *H*, coming in contact with a revolving or sliding body, will become heated by friction, and thus melt the thick oil or tallow that is in the cup or casing *A*. It also serves to prevent the oils from feeding too freely. The stem of the plug-valve *p* extends up through the tube *E*, and through the central extension, *e*, on the boss of the screw-cap *D*, and is surrounded by a spiral spring, *I*, in the central tube, *E*, which keeps the valve normally pressed toward its seat.

The letter *K* indicates a sleeve fitting within the extension of the central boss of the screw-cap *D* and around the stem of the plug-valve *p*. The said sleeve *K* is longitudinally slotted on diametrically-opposite sides, so as to engage the ends of a pin, *s*, passing through the valve-stem. The said sleeve *K* is provided on its upper end with a head, *t*, and with lateral arms *u*, the head having a tapering recess in it, in which is adapted to turn the tapering plug *v*, which is screw-threaded internally and engages the upper screw-threaded end of the rod or stem of the plug-valve *p*, before mentioned. The said plug *v* has a milled wheel, *w*, at its upper end, by which it may be readily turned.

The central boss, *d*, of the screw-cap *D* of

the casing or outer cup is provided with filling openings a' , through which the internal cup may be filled, and the lateral arms on the head t are so arranged that they will rest over 5 said openings except when the valve is set for feeding, so as to prevent the filling of the inner cup unless the valve is so set. One of the lateral arms is provided with a vertical opening, in which is inserted a pin, b' , which extends only partly through, leaving a recess below, which fits over a similar pin, c' , secured to the central boss, d , of the screw-cap when the valve is set for feeding. The pin b' serves as an indicator to enable the operator to determine which of the lateral arms is recessed to fit over the pin c' .

To set the valve for feeding, the parts are brought to the position shown in Fig. 1. Thick or heavy oil is then poured into the 20 outer casing through one of the lower windows and thin or light oil into the inner cup through the feed-openings in the central boss of the cap. The amount of the oil fed may then be regulated by turning the plug v , which 25 raises or depresses the plug-valve.

As constructed, it is evident that the engineer, in order to charge his cup, is compelled to set the valve for feeding, and hence is obliged to have it always in operating condition, so that no accidents can result from negligence or carelessness.

Having thus described my invention, what I claim, and desire to secure by Letters Patent, is—

35 1. In an automatic lubricating cup, the com-

bination, with the outer casing or cup and the inner cup, of the plug-valve and sleeve surrounding the valve-stem, the perforated screw-cap, the sleeve K , provided with a head, t , and with lateral arms, and the internally-screwed 40 threaded plug v , substantially as specified.

2. The combination, with the outer casing or cup and the inner cup, of the plug-valve, the central tube, E , a spring surrounding the valve-stem, the plate G , washer j , the screw-cap D , having a central boss, the slotted sleeve K , provided with a recessed head and lateral arms, and the pin on the boss of the screw-cap, adapted to engage with a recess in one of the arms, substantially as and for the purpose specified.

3. The combination, with the outer casing or cup, of the perforated screw-cap D , with its boss d , extension e , and pin c' , the inner cup, the central tube, E , the plate G , whereby the 55 said inner cup is suspended in the outer casing or cup, the regulating plug-valve, the slotted sleeve, through which the valve-stem and its pin s pass, recessed head t , having the regulating plug v , and the lateral arms u , one of said arms being recessed to receive the pin c' , substantially as and for the purpose specified.

In testimony that I claim the foregoing as my own I affix my signature in presence of two witnesses.

ALDEN D. KILBORN.
